Patented June 6, 1922.

FIG. 1.

FIG. 2

FIG. 3

INVENTOR.

BY Herman O. Reidenbach

Clement P. Tritton, ATTORNEY.

UNITED STATES PATENT OFFICE.

HERMAN O. REIDENBACH, OF DETROIT, MICHIGAN, ASSIGNOR TO L. A. YOUNG INDUSTRIES, INC., OF DETROIT, MICHIGAN, A CORPORATION OF MICHIGAN.

SPRING-SEAT CONSTRUCTION.

1,418,469.

Specification of Letters Patent. Patented June 6, 1922.

Application filed June 13, 1921. Serial No. 477,106.

To all whom it may concern:

Be it known that I, HERMAN O. REIDENBACH, a citizen of the United States, residing at Detroit, in the county of Wayne and State 5 of Michigan, have invented certain new and useful Improvements in Spring-Seat Constructions, of which the following is a specification.

It is frequently desirable in spring seat 10 constructions to provide a pliable top which will afford substantially unbroken support to applied upholstery while at the same time the members of the structure are firmly united so as not to be displaced by the shocks 15 of severe usage.

This invention relates to a spring seat construction and more particularly to an arrangement of parts whereby a pliable top is obtained that supports applied covering 20 and filling in such a way that it does not tend to sag between the springs while the springs themselves are free to act independently in a measure, but at the same time are anchored rigidly against lateral displacement 25 without the aid of clips or other like fastening means.

The invention consists in the matters hereinafter set forth and more particularly pointed out in the appended claims.

30 In the drawings, Fig. 1 is a plan view, partially broken away and in section to disclose the lower frame construction, of a spring seat that embodies features of the invention;

35 Fig. 2 is a view in detail of a transverse frame member with the end turns of springs attached thereto;

Fig. 3 is a view in section taken on or about line III—III of Fig. 2.

40 Referring to the drawings, a base 1 is formed of suitable design with upright body springs 2 mounted thereon. The springs are disposed in rows and each pair of two adjacent rows are interconnected by a pliant 45 frame strip 3 of sufficient width not only to overlap the adjacent upper turns of the springs, but also to bridge over the interstices between the springs so as to prevent upholstery that is applied to the structure, 50 from sagging between the springs.

Where the strip overlies the upper or end turns 4 of the springs, the margins of the strip are inbent as indicated at 5 and crimped around the turns while at the ends, 55 the strip is bent over as indicated at 6 to

enfold a rim 7, the latter of which is likewise attached to certain end turns of the springs by clips 8 or other suitable means.

The base of the structure may be of any preferred type but as herein indicated, is a 60 replica of the upper rim frame. A border member 9 is spanned by pliable strips 10, the end portions 11 of which are bent around the rim while the base turns 12 of the body springs which are seated partially on the strips, are secured by the inturned or inbent marginal portions 13 thereof, there being other fastening members 14 where necessary to hold the outer springs to the rim. 65

When in use, any weight that is carried 70 by the springs is sustained not only at the point of application, but also at places remote thereto, since the pliable strips cannot be sagged appreciably, as they are stretched between the sides of the rim frame, while 75 local deformation of each spring is possible since the strips bend slightly to permit this. The connection between the strip and springs reinforces the strip at this point of attachment because of the triple layers of 80 material at these points. Between the springs, the strip is freely bendable so far as the method of attachment to the rim frame permits this.

As a result, a spring structure is obtained 85 that presents a smooth exterior with broad supporting members for applied upholstery, while at the same time, the top is soft and resilient. The springs are secured in position without the aid of clips, save at the few 90 points of attachment in the rim frame.

Obviously changes in the details of construction may be made without departing from the spirit of the invention and I do not care to limit myself to any particular form 95 or arrangement of parts.

I claim as my invention:

1. A spring cushion structure including a border frame, cross strips of pliant metal secured at their ends to said border frame, 100 and coiled springs arranged in rows with the end coils of springs of adjacent rows disposed side by side and overlapping said cross strips, the opposed edges of said cross strips within the coils being folded inwardly 105 upon and conformed to the coils, the outer rows of springs being secured to the members of the frame parallel to said strips.

2. A spring cushion structure including a border frame, cross strips of pliant metal 110

secured at their ends to said border frame, and coiled springs arranged in rows with the end coils of springs of adjacent rows side by side and overlapping said cross strips, the opposed edges of said cross strips lying within the coils being folded inwardly thereon, the remaining portions of the strips being flat and pliant.

3. A spring cushion structure including a border frame, cross strips of pliant metal

secured at their ends to said border frame, and coiled springs arranged with their end coils overlapping said cross strips, the edges of said cross strips lying within the coils being folded thereon, the outer rows of 15 springs being secured to the portions of the frame parallel to said strips.

In testimony whereof I affix my signature.

HERMAN O. REIDENBACH.
